GEAR DRIVING MEANS FOR CENTRIFUGAL MACHINES

Charles A. Olcott, West Milford, N. J.

Application December 3, 1943, Serial No. 512,683

4 Claims. (Cl. 192—3.5)

This invention relates to centrifugal machines for separating solid materials from containing liquids and more specifically to driving and controlling means therefor.

It is an object of this invention to provide novel gear driving means for a centrifugal machine.

In Patent 2,314,286, issued March 16, 1943 to Charles A. Olcott, there is disclosed a gear drive arrangement for driving each of a plurality of centrifugal machines positioned in a group from a main drive shaft. The gear drive arrangement has different gear ratios for the starting and full speed operation of the machine and control means is provided which automatically establishes the proper gear ratio for operation of the centrifugal machine at the desired time. A centrifugal governor is provided and arranged so that it prevents the operation of the machine at a speed in excess of a predetermined maximum. In the patented arrangement, the axis of the main drive shaft is in the same plane as the axis of each of the shafts driving the spindles of the centrifugal machines. The present invention, in one of its more important aspects, relates to driving and controlling means for a centrifugal machine arrangement wherein the main drive shaft is not in the same plane as the axis of each of the shafts used to drive these spindles.

It is another object of the present invention to provide a centrifugal machine gear drive arrangement between two shafts whose axes are not in the same plane.

In a specific embodiment of the invention, there is provided, by way of example for illustrative purposes, a two-speed gear drive for the operation of a plurality of centrifugal machines from a common drive shaft, the axis of this drive shaft being in a plane which is parallel to the plane containing the axis of the shaft (called hereinafter the auxiliary drive shaft) used to drive the spindle of at least one of the centrifugal machines. Suitable gearing, such as that commonly called "hypoid" gearing, is utilized to drive this auxiliary shaft from the main drive shaft and the two shafts cross each other (without, of course, touching one another). Two sets of two gears each are utilized and these four gears are so mounted that they form roughly a rectangle, making a convenient arrangement for assembly and maintenance. The auxiliary shaft projects through the gear casing and has attached thereto a centrifugal governor to prevent the speed exceeding a pre-

determined maximum. The fact that the governor is located outside the gear casing assures easy adjustment and repair of this member.

The invention will be more readily understood by referring to the following description taken in connection with the accompanying drawing forming a part thereof in which the single figure is a view partly in section and partly diagrammatic of a gear driving means in accordance with this invention for a single centrifugal machine of a battery, the gear driving means serving to connect the centrifugal machine to the main driving shaft for the battery of machines.

Referring more specifically to the drawing, there is shown, by way of example for illustrative purposes, a two-speed gear drive for a centrifugal machine, the gear drive being constructed in accordance with the invention. This centrifugal machine, which has a rotating basket 10, can be, for example, one of a battery of such machines driven from a main drive shaft 11 which is operated by means (not shown) such as, for example, a synchronous electric motor or a hydraulic motor. To drive each basket 10 from the main drive shaft 11 there is provided gearing means comprising a gear casing or housing 12 having openings in which are fitted roller bearings 13 and 14. Mounted in these roller bearings and extending to opposite sides thereof are sleeves 15 and 16, carrying bearings 17, 18, 18A and 19, in which the shaft 11 is rotatably mounted. Keyed to the sleeve 15 at opposite ends thereof are a clutch member 20 and a gear 21, while keyed to the sleeve 16 at opposite ends thereof are a clutch member 22 and a gear 23, the gear 23 having a smaller number of teeth than the gear 21. Cooperating with the clutch members 20 and 22 are clutch members 24 and 25, respectively, which are keyed to rotate with the main drive shaft 11 and are movable longitudinally thereof, being operated by levers 26 and 27, respectively, to engage and disengage their cooperating clutch members 20 and 22, respectively.

The levers 26 and 27 are pivotally mounted on the gear casing 12 and are connected by a link 28 which has a pivotal connection with the lever 27 and a pin and slot connection with the lever 26, the lengths of the link 28 and the slot therein being such that either pair of cooperating clutch members may be engaged and both may be disengaged but both cannot be engaged at the same time. To operate the levers 26 and 27 there are provided cylinders 29 and 30 mounted in extensions of the walls of the gear casing 12 and hav-

ing pistons therein connected by rods 31 and 32 to the levers 26 and 27, respectively. Springs 33 and 34, connected to the levers and cylinders, serve to operate the levers to separate the cooperating clutch members. Pressure for operating the pistons in cylinders 29 and 30 is supplied through a pipe line 35 connected by branch pipes 36 and 37 to the cylinders. Valves 38 and 39, each having, as shown in the drawing, three entrance or exit ports in the outer casing and an inner port in a diaphragm therein, are mounted in the branch pipes and are operated by solenoids 40 and 41, respectively, to positions for supplying pressure to the cylinders and, upon the solenoids being de-energized, are returned by the springs 42 and 43, respectively, to positions for venting air from the cylinders. In the drawing, valve 39 is shown in the position in which air pressure from the pipe 35 is supplied to the cylinder 30 through the middle port in the valve 39 and pipe 37 while valve 38 is shown in the position to vent air from the cylinder 29 through the pipe 36 and the escape port shown at the left of the valve casing.

The gears 21 and 23 mesh with other gears 44 and 45, respectively, fixed on a tubular shaft 46. The axis of the shaft 46 is not in the same plane with the axis of the main drive shaft 11 and the two shafts cross one another, the shaft 46 preferably projecting through the top of the gear casing 12. The gears 21, 23, 44, and 45 can be of any form suitable for driving one shaft from a second shaft whose axis is not in the same plane as the axis of the first shaft. By way of example gears known as "hypoid" gears can be used. Hypoid gears per se are well known and need no further description at this point as their construction is described in any standard gear textbook. As an example, reference is made to the text entitled "Standard gear book" (1935) by Reginald Trautschold, pages 143 and 144. The use of gears of this type makes it possible to have the shafts 46 and 11 cross one another. It will be noted from the drawing that gears 21, 23, 44 and 45 form roughly a rectangle, a construction which adds to ease of assembly and maintenance.

The shaft 46 is journaled in ball-bearings 47 and 48 fixed in inner and outer walls, respectively, of the casing 12. The shaft 46 has fixed at its lower end a flange or clutch member 49, the lower face of which is provided with a friction surface or friction inserts 50. To the upper end of the shaft 46, outside the casing 12, there are pivotally connected the inner ends of links 51, the outer ends of which are pivotally connected to intermediate points of the lever arms 52 of a centrifugally operated means, one end of each of the arms 52 having a weight 53 attached thereto while the other end of each of the arms is pivotally connected to the shell or outer race 54 of a ball bearing 55, the inner race 56 of which is fixed on the end of a shaft or rod 57. The rod 57 is slidably mounted in the tubular shaft 46 and projects below the lower end of the shaft 46 sufficiently to have fixed thereon a clutch member 58. Encircling the shaft 57 and confined between the bearing 55 and the end of the shaft 46 is a spring 59 of such strength and under such compression as to overcome the downward thrust of the shaft 57 produced by the centrifugal action of the weights 53 and hold the clutch member 58 in engagement with the clutch member 49 to be driven thereby until the shaft 46 attains a speed slightly in excess of the speed

necessary to rotate the basket 10 at its maximum speed. When the speed of the shaft 46 becomes excessive, the centrifugal action of the weights 53 overcomes the action of the spring 59, causing the spring to be compressed and the shaft 57 lowered to separate the clutch members 49 and 58.

Fixed to the clutch member 53 are pins 60 which slidably engage in openings in a flange 61 fixed on the shaft 62 which drives the basket 10. A brake drum 63 is secured to the shaft 62 and acting thereon is a brake shoe 64 operated by the piston of a brake cylinder 65. Pressure for operating the brake is supplied from the pipe line 35 through the branch pipe 66 and is controlled by a valve 67 operated by a solenoid 68. The valve 67 can be of the same type as the valves 38 and 39. The solenoid 68, when energized, operates valve 67 to supply pressure to the brake cylinder against the action of a spring 69 and when the solenoid is deenergized, the spring returns the valve to a position (the position shown in the drawing) in which the pressure is vented from the brake cylinder to the atmosphere.

In order to permit easy access to the gears, joints 70, 71, 72, and 73 are provided. These joints make it possible for a whole shaft with its bearing and corresponding gear to be pulled out of the gear case without disturbing the other.

The clutch and brake solenoids shown in the drawing can be energized and de-energized to control the operation of the clutches and brake by means of electrical circuits such as are shown and described in the above-identified Olcott patent. These circuits comprise no part of the present invention so they are not shown in the drawing.

The operation of the gear mechanism shown in the drawing will now be described. When the basket 10 is at rest, the solenoid 68 is energized causing the brake shoe 64 to be applied to the drum 63 on the shaft 62 by means of air pressure from the pipe 35 applied through the middle port of the valve 67 (the right hand port being closed) to the pipe 66 and the cylinder 65. To start rotation of the basket 10, the solenoid 68 is de-energized permitting the air brake valve 67 to be operated to vent pressure from the brake cylinder 65 by way of the right hand port of the valve 67 and release the brake. The solenoid 41 is energized to the position shown in the drawing, operating valve 39 to supply pressure to cylinder 30 by way of the middle port of the valve 39, operating lever 27 against the action of spring 34 to engage the clutch members 25 and 22, causing gear 23 to be driven by shaft 11 and operating through gear 45, sleeve 46, clutch members 49 and 58 and shaft 62 to start rotation of the basket 10 of the centrifugal machine.

The ratio of gears 23 and 45 is such that they will drive the basket at substantially half-speed and by proper timing means such as is shown and described in the above-mentioned Olcott patent the rotation of the basket is continued at that speed until the point in the operating cycle for full speed drive is reached. At this point the circuit of the solenoid 41 is interrupted to permit valve 39 to be operated by its spring 43 to the position for venting pressure from the cylinder 30 through the opened right hand port of the valve 39 to allow spring 34 to operate lever 27 to separate the clutch members 25 and 22. Solenoid 40 is then energized, operating valve 38 to close the left hand port and

thus to supply pressure to cylinder 29 through the opened middle port of the valve 38 for the operation of lever 26 and the engaging of the clutch members 24 and 20. The engaging of these two clutch members causes the gear 21 to be driven by the shaft 11 and through gear 44, shaft 46, clutch members 49 and 58 and shaft 62 to drive the basket at full speed. The basket is driven at this speed for a predetermined period of time. At the expiration of this period, solenoid 40 is de-energized permitting the valve 38 to be operated to vent pressure from the cylinder 29 through the left hand port of the valve 38 and the lever 26 to be operated by spring 33 to separate the clutch members 24 and 20 so that the basket 10 is no longer driven at full speed from the shaft 11. Solenoid 41 is then energized causing the operation of lever 27 to engage clutch members 25 and 22.

As the basket 10 is still rotating under its momentum at substantially full speed and as the clutch members 25 and 22 and gears 23 and 45 would drive the basket 10 at only half speed, the basket 10 tends to speed up the shaft 11 when the clutch members 25 and 22 are engaged and the inertia of the shaft 11 and the other baskets connected thereto exert a braking action on the basket 10 which is connected to the shaft through the clutch members 22 and 25. Should it happen that a number of baskets are simultaneously changed from the condition of being driven by the shaft 11 through their gears 21 and 44 to that of being connected to the shaft 11 through their gears 45 and 23, their momentum might be sufficient to raise excessively and almost instantly the speed of shaft 11 and of any baskets driven therefrom through their gears 21 and 44. The increase in the speed of the basket excessively above its normal full speed causes the centrifugal action of the weight members 53 to overcome the resistance of spring 54 and lower shaft 57 to separate the clutch members 49 and 58 and disconnect the basket 10 from the drive shaft 11, thus preventing the basket 10 from being rotated at a dangerous rate. Rotation of the shaft 46 at an excessive speed preferably causes a control switch (not shown but which may be part of the controlling apparatus shown in the Olcott patent) to be opened and interrupt the circuit of the solenoid controlling the operation of the clutch operating lever and maintain the circuit open as long as the speed of the shaft remains in excess of the predetermined limit.

In the usual operation the speed of shaft 11 is not raised sufficiently to cause operation of the centrifugal means for any of the baskets connected to the shaft 11 and the speed of the basket whose connection to the shaft has been changed is gradually reduced to half speed by the time the circuit of solenoid 41 is interrupted, permitting the clutch members 25 and 22 to be separated, and the solenoid 68 is energized, causing the brake shoe 64 to be applied to the drum 63 to stop operation of the basket 10 and bring it to its initial position.

The arrangement of gear drive and the control means therefor provides for building up the speed of the basket from rest to half-speed by means of the lower gear ratio provided, thus greatly lessening the load thrown on the driving motor at the start of each machine and greatly reducing the wear and maintenance on the clutches and gearing. It also permits maximum acceleration of the basket to half-speed and the building up of the speed of the basket from half- 75

speed to full speed at the usual rate of acceleration. Changing to the lower gear ratio in decelerating the machine causes the one being slowed to aid in driving the other machine and to reduce to some extent the power consumption of the driving motor during the slowing of the machine from full to half-speed. The various centrifugal means 53 insure the speed of all baskets being kept below an excessive rate at this time. The timing devices described in the Olcott patent insure the various operations taking place at the earliest possible time.

By using hypoid gears 21, 23, 44, and 45 (or other means for performing the same function), instead of the more conventional gear and pinion arrangements of the Olcott patent, an arrangement is provided wherein the shaft 46 crosses the shaft 11 and projects out the top of the gear casing. This makes it possible for the weights 53 and their associated mechanisms to be located outside the casing, thus making access thereto simple for adjustment and repair, and also makes it unnecessary to line up the vertical axes of all the baskets 10 in a single plane. By means of the joints 70 to 73, inclusive, and the rectangular arrangement of the gears, a gear can often be changed without tearing down the whole drive mechanisms. Various other advantages of the arrangement in accordance with the invention will readily occur to the workers in the art.

What is claimed is:

1. In a centrifugal machine, a horizontal drive shaft, a vertical driven shaft having an axis 35 which is in a vertical plane displaced from the vertical plane containing the axis of said drive shaft, a driving mechanism constructed and arranged to drive the machine from said horizontal shaft at both a high speed and a low speed, 40 said mechanism including two sleeves surrounding the main shaft, two hypoid gears of different sizes respectively mounted on said sleeves, a tubular vertical shaft having the same axis as said machine and crossing said main axis, two hypoid 45 gears of different sizes mounted on said tubular shaft and being constantly in mesh respectively with the gears on said sleeves, clutch means for connecting said tubular shaft to the shaft of said machine, and clutches associated with said sleeves for selectively causing said sleeves to rotate with said main shaft, a housing for said sleeves, clutches, gears and at least a portion of each of said shafts, and centrifugally operated 50 means driven by said tubular shaft and located outside said housing for disconnecting said tubular shaft from said machine when the speed of said tubular shaft exceeds a predetermined limit.

2. The combination of elements as in claim 1 in which said centrifugally operated means operates a rod slidably mounted in said tubular shaft for disengaging the clutch means between said tubular shaft and the shaft of said machine when the speed of said tubular shaft exceeds said predetermined limit.

3. The combination of elements as in claim 1 in which said four hypoid gears are arranged to form roughly a rectangle and said sleeves and the gears associated therewith are removably supported from different parts of said housing whereby one sleeve and the gear mounted thereon can be removed for repair or replacement without disturbing the other sleeve and the gear mounted thereon.

4. In an upright centrifugal machine having a

vertical shaft, a main horizontal shaft for driving said machine, the axis of said main shaft being in a vertical plane which is displaced from the vertical plane containing the axis of said machine, a driving mechanism constructed and arranged to drive the machine from said horizontal shaft at both a high speed and a low speed, said mechanism including two sleeves surrounding said main shaft, two gears of different sizes respectively mounted on said sleeves, a tubular vertical shaft having the same axis as said machine and crossing said main axis, two gears

5 mounted on said tubular shaft and constantly meshing respectively with the gears on said sleeves, means for connecting said tubular shaft to the shaft of said machine and means for selectively causing said sleeves to rotate with said main shaft, and centrifugally operated means driven by said tubular shaft and located above said main shaft for disconnecting said tubular shaft from said machine when the speed of said

10

tubular shaft exceeds a predetermined limit.

CHARLES A. OLcott.
